CLAIM

The ornamental design for a lamp pole cover, as shown and described.

DESCRIPTION

FIG. 1 is a perspective view of a lamp pole cover incorporating my new design;

FIG. 2 is a front elevation view thereof;

FIG. 3 is a right side view thereof;

FIG. 4 is a rear elevation view thereof;

FIG. 5 is a left side view thereof;

FIG. 6 is a top plan view thereof; and,

FIG. 7 is a bottom plan view thereof.

The broken lines shown in the drawings illustrate portions of the lamp pole cover that form no part of the claimed invention.
